CLAIM

The ornamental design for a portable computer, as shown and
described.

DESCRIPTION

FIG. 1 is a front bottom perspective view of a portable computer showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines depict environmental subject matter only
and form no part of the claimed design. The dot-dash broken
lines and brackets represent an omitted portion in length in the
claimed design.
